REFRIGERATING APPARATUS

Lindsay H. Browne, Pittsford, N. Y., assignor to
Kellogg Compressor and Manufacturing Cor-
poration, a corporation of New York

Application August 8, 1936, Serial No. 94,929

2 Claims. (Cl. 62—115)

This invention pertains to improvements in refrigerating apparatus.

An object of the invention is to provide improved apparatus forming a closed refrigerating system.

Another object is to provide a closed refrigeration system including improved silencing means.

Another object is to provide an improved high side or condensing unit.

Another object is to provide a device of the above character including an improved unitary motor-compressor structure.

A further object is to provide improved sealing means between the motor and compressor.

Another object is to provide improved compressor valve structures.

Another object is to provide an improved cylinder head structure and improved means for securing the head, discharge valve plate and cylinder together.

A further object is to provide an improved resilient mounting for the high side apparatus.

A still further object is to provide a high side unit of the above type which is compact, simple and cheap to manufacture and which may be readily adapted for different types of installation.

Other objects and advantages of the invention will become apparent during the course of the following description in connection with the accompanying drawings, in which—

Figure 1 is a side view of a preferred form of the invention, partly in section;

Figure 2 is an end elevation of the same;

Figure 3 is an enlarged detail sectional view showing the seal, shaft and crank structures;

Figure 4 is a detail end elevation of the bearing bushing;

Figure 5 is a cross sectional view of the discharge valve and plate showing the valve in open position;

Figure 6 is a similar view showing the valve in closed position;

Figure 7 is a plan view of the same;

Figure 8 is a detail view showing the discharge muffler in longitudinal section together with its terminal connecting means;

Figure 9 is an end elevation of the muffler;

Figure 10 is a detail sectional view of the piston structure and upper end of the connecting rod;

Figure 11 is an end elevation of the condensing unit showing an alternative arrangement of the compressor;

Figure 12 is a diagrammatic representation of

a closed refrigeration system including the apparatus; and

Figure 13 is a detail sectional view of an alternative shaft and seal structure.

Referring to Figures 1 and 2, the numeral 20 indicates a base which may be provided with springs 21 to form a resilient mounting for the condensing or high side unit. Brackets 22 and 23 are secured to the base 20 and form a support for the motor-compressor assembly in a manner to be hereinafter described.

An electric motor 24 comprising an outer shell 25 carrying the usual stator coils 26, has a rear end plate 27 on which is formed a bearing housing 28 containing a suitable bearing rotatably supporting one end of a shaft 29 on which is mounted the rotor 30. A unitary compressor block 31 comprises an end plate portion 32, a crank case portion 34, and a cylinder 35. The end plate portion 32 is secured to the motor shell 25 in the manner common to electric motor construction, as, for example, by bolts 33, Figure 2.

A sleeve 36 is disposed on a reduced extension 37 of the motor shaft 29 and forms a journal 25 rotatably mounted in a bearing bushing 38 secured in a boss 39 extending from the crank case 34 toward the motor 24.

A crank member 40 is screwed on the threaded end 41 of the extension 37, clamping the sleeve 36 longitudinally against a collar 42 which in turn presses against a gasket 42a backed by a shoulder 29a on the shaft 29. A metallic bellows member 43, surrounding the sleeve 36, has thereon a flange 44 which is clamped against a gasket 44a on the end of the boss 39 by means of an internally shouldered nut 45 screwed on the threaded periphery of the boss.

A ring 46 secured to the end of the bellows 43, as shown in enlarged detail in Figure 3, carries an annular, shoe 47 engaging the face of the collar 42. A compression spring 48 disposed between the flange 44 and the ring 46 urges the shoe 47 into engagement with the collar 42 as noted, the mean diameter of the shoe face in contact with the collar being substantially the same as that of the bellows 43. The nut 45 has formed thereon a slotted cylindrical extension 49 slidably engaging the outer circumference of the ring 46 and adapted to maintain the latter and its shoe 47 in concentric alignment with the shaft 29 and collar 42.

An oil hole 50, Figure 3, leads from a pocket 51 formed in the crank case 34 above the shaft extension 37 to an annular oil groove 52 and to

an intersecting helical oil groove 53 in the bushing 38.

Referring to Figure 4, a longitudinal slot or groove is formed in the outer circumference of the bushing 38 and extends throughout the full length thereof, the groove 54 being located near the top of the bushing.

The crank member 40 carries a crank pin 55, Figures 1 and 3, a counterweight 56 being attached to the crank member 40 opposite the crank pin. A piston 57, Figures 1 and 10, of a type fully described and claimed in copending application Serial No. 94,930, filed August 8, 1936, is slidably disposed in the cylinder 35 and comprises an outer barrel 58 in which a trunnion member 59 is fastened by means of a screw 60 through the head 61 of the barrel. A wrist pin 62, in the trunnion member 59, has rockably mounted thereon the bushed upper end 63 of a connecting rod 64. The lower end of the connecting rod is equipped with a bushing 66 rotatably mounted on the crank pin 55. A downwardly extending oil splasher 67 is fastened to the lower end 65 of the connecting rod. The piston barrel 58 is provided with annular oil grooves 58a in its periphery to aid in proper lubrication of the cylinder wall and to maintain a seal against leakage of gas past the piston.

An annular discharge valve plate 68 has a lower cylindrical portion 69 extending into the top of the cylinder 35. An upper cylindrical portion 70 of the valve plate 68 fits into a chamber 71 of the cylinder head 72.

Referring to Figure 2, it will be seen that a yoke 73 is disposed across the top of the cylinder head 72. A pair of links 74 and 75 are pivoted to lugs 76 by means of pins 77 on the crank-case 34 and are also articulated to the end of the yoke 73 by means of pin 78. A screw 79, threaded through the middle of the yoke 73, has a concave lower end 80 bearing on a ball 81 sunk into the top of the head 72 above the center line of the cylinder 35 as shown in Figure 1. When the screw 79 is screwed downward in assembly, the valve plate 68 is firmly clamped between the head 72 and cylinder 35, sealing gaskets 82 and 83 being provided respectively above and below the plate.

It will be seen that the use of the floating yoke 73 and the clamping screw 79 bearing on the central ball 81 provides a firm and even pressure on the clamped surfaces of the head 72, plate 68 and cylinder 35 and eliminates the use of the usual cylinder head bolts, thereby making possible a simple structure and facilitating assembly while at the same time assuring tightness of the gaskets.

The extension of the plate 68 into both the cylinder 35 and the head 72 assures concentricity of these parts and also assists in maintaining tightness of the gaskets 82 and 83, as no edges of the latter are exposed directly to internal pressure.

The crank-case 34 has an opening 84 through which the internal working parts may be inserted during assembly. A closure plate 85 covering the opening 84 is secured to the crank-case 34 by means of cap screws 86. An annular extension 87 of the closure plate is inserted in a ring 88 of rubber or other suitable resilient material secured to the bracket 23 by means of a clamp 89, as shown in Figure 2. A similar resilient ring 90, Figure 1, is clamped to the bracket 22 and concentrically supports the rear end of the motor 24.

It will be seen that the similar rings 88 and 90 and their brackets 23 and 22 provide a concentric resilient mounting for the motor-compressor unit on the base 20.

The suction and discharge valve structures of 5 the compressor are as follows:

Referring to the enlarged sectional view of the piston Figure 10, it will be seen that the head 61 of the barrel 58 has formed in its upper face an annular groove 91 from which holes 92 10 lead downward into the interior of the barrel. A suitable baffle 136 is provided in the lower part of the barrel 58 to prevent excess oil from being splashed into the holes 92. A ring plate valve 93 of this metal is retained on the upper face of the 15 piston by the head 94 of the screw 60, the ring plate acting as a closure over groove 91. A narrow washer 95 of thickness slightly greater than the ring plate 93, is clamped under the screw head 94 within the ring plate and acts as a 20 spacer. During the downward or suction stroke of the piston, the entire ring plate 93 is allowed a slight upward movement under the screw head 94 to permit the passage of vapor through the 25 holes 92, groove 91 and around the periphery of the ring plate. By this means, an ample annular area is provided for free entry of gas to the cylinder, but due to the lightness of the ring plate and its restricted movement, the suction 30 valve operation is performed without noise.

The discharge valve plate 68, Figures 1, 5, 6 and 7, has formed in its lower surface a depression 96 to accommodate the screw head 94 when the piston is at the top of its stroke, thereby permitting the clearance space to be held to a 35 minimum. The flat upper face 100 of the plate 68 has formed therein an annular groove 97 surrounding the central discharge passage 98. A cantilever leaf valve 99 is secured at one end to the upper face 100 by means of the screw 101, 40 with its other end overlapping the discharge passage 98. A laterally tapered limiting spring finger 102 is fastened to the plate 68 by means of a screw 103 diametrically opposite the screw 101 and is spaced from the plate by an underlying 45 washer 104.

The spring finger 102 is bent downwardly throughout part of its length and terminates in a downwardly convex end portion or tip 105 engaging the top of the valve leaf 99 in line with 50 the discharge passage 98.

It will be understood that the thickness of the leaf valve 99 and the limiting spring finger 102 is exaggerated in Figures 5 and 6 for purposes of clarity, their actual thickness being 55 very small.

During the compression stroke of the piston, compressed gas or vapor is forced upward through the passage 98. The pressure against 60 the lower face of the leaf valve 99 raises the latter from its seat 106 defined by the grooves 97 and central passage 98, allowing gas to pass upward into the discharge chamber 71. As the leaf valve 99 is raised it flexes the finger 102 by 65 forcing the latter's forward end upward. As valve 99 continues to rise, its line of contact with finger 102 shifts to the right, Figures 5 and 6, as the comparatively narrow bent portion of 102 tends to flatten upward. This shifting to the 70 right of the line of contact occurs with a substantially rolling action as the two leaves flex together and results in increasing resistance to the rise of the valve 99 due both to the shortening of the effective cantilever length of finger 75

102 and to its increasing width at the contact line.

The above action continues until at extreme open position the valve leaf 99 and finger 102 mutually form an arch as shown in Figure 5. When discharge is completed the reverse action occurs, the two leaves flexing downward with a substantially rolling contact until leaf 99 engages its seat 106, the contact between leaf 99 and seat 106 also occurring with a slight rolling motion from left to right as the leaf loses its upward curvature. The end portion 105 of finger 102 holds the leaf 99 lightly but firmly and evenly on its seat while the valve is in closed position, due to the finger's pressure on the leaf directly above the center of the discharge passage 98.

While the actual amplitude of valve rise during discharge is very small, the above interaction of the parts has been described in detail because together with the small inertia of the parts, it results in positive and quiet valve action at the comparatively high compressor speed provided by the directly connected motor, at the same time permitting discharge of the gas with a minimum of resistance.

The cylinder head 72, Figure 1, has a lateral discharge shut-off valve 108, Figures 1 and 2, of suitable type provided with the usual sealing cap 109.

30 A muffler or silencer 110, shown in detail in Figure 8 comprises an outer shell 111 enclosing a chamber 112. A tubular member 113, extending into the chamber 112, has a flange 114 secured to the outer shell 111 and forming one end of the silencer. The tubular member 113 has in its barrel a number of perforations 115 and is closed at its inner end, the outer end thereof being connected to the outlet 116 of the discharge shut-off valve 108. A tubing union elbow 117 screwed 40 into the end of the shell 111, forms the outlet from the chamber 112.

From the union 117 a tube 118 leads to an air-cooled condenser 119 secured to the base 20 beyond the end of the motor 24. A fan 120 on the rear end of the shaft 29 adjacent the condenser 119 is adapted to furnish the latter with a draft of cooling air when the device is in operation. From the bottom of the condenser 119 a liquid tube 121 leads through a union 122, Figure 1, into a suitable receiver 123 fastened to the base 20 by means of brackets 124 as shown in Figure 2.

The receiver 123 is provided with a liquid outlet stop valve 125 adapted to be connected in the usual manner to any suitable type of cooling unit or low side such as that shown diagrammatically in Figure 12 and including the expansion valve 137 and cooling coil 138. The valve 125 carries an inlet tube 126, Figure 2, extending downward 50 inside the receiver 123 to a point near the latter's bottom. A suction shut-off valve 127 of any suitable type secured to the crank case 34 and leading into the interior thereof is adapted to be connected to return end of the cooling coil or unit 138 as also illustrated in Figure 12.

A bracket 128, fastened to the outer shell 25 of motor 24, supports an oil tube 129 leading to the rear bearing housing 28 and provided with a closure cap 130. The provision for applying oil 70 to the motor bearing is thus located at a point remote from the fan 120 and in an easily accessible position. The bracket 128 may be provided with a loop 131 adapted to support a capacitor 132 for the motor 24 when the latter is intended for use with alternating current.

In operation, the motor 24 revolves the crank member 40 to reciprocate the piston 51, drawing gaseous refrigerant into the crank case 34 through the suction valve 127 and forcing it out through the discharge shut-off valve 108 into the interior 5 of the tubular member 113. From the interior of the member 113 the gas diffuses through the perforations 115 into the chamber 112, passing thence through the elbow union 117 and tube 118, to the condenser 119 where it is liquefied 10 by the cooling effect of the air draft provided by the fan 120. From the bottom of the condenser 119 the liquefied refrigerant passes through the tube 121 into the receiver 123; thence outward through the tube 126, valve 125 to the line (not 15 shown) leading to the cooling unit.

The purpose of the muffler or silencer 110 is to eliminate the audible pulsations of the gas passing to the condenser 119 and thereby promote quietness of operation, it having been found that with 20 high speed compressor operation the vibratory discharge may be objectionably audible through the condenser or receiver in devices not provided with muffling means. The diffusion of the gas through the perforations 115 into the enlarged 25 chamber 112 breaks up the impulses and promotes a smooth and quiet flow of gas to the condenser as well as even and continuous condensation and flow of liquid to the receiver.

As the compressor is driven at high speed, the 30 splasher 67 splashes oil into the pocket 51 from which the oil runs down the hold 50 into the oil grooves 52 and 53. The helical advance of oil groove 53 is in such a direction that as the journal sleeve 36 rotates in the bushing 38 oil is 35 carried along the groove 53 into the interior of the seal bellows 43, providing a supply of lubricant to the shoe 47 pressing against the revolving collar 42. The oil carried into the interior of the bellows in the manner described 40 accumulates in the latter until it rises to the level of the groove 54 in the outside of the bushing 38. Thereafter, additional oil entering the bellows causes a flow back through the groove 54 to the interior of the crank case 34. In its exit from 45 the groove 54, the oil provides lubricant for the thrust of the crank member 40 against the end of the bushing 38. As oil is supplied to the inside of the bellows, rotation of the sleeve 36 and collar 42 tends to throw oil centrifugally into the sealing 50 joint, thus assuring proper lubrication thereof.

It will be then seen that the foregoing provides a continuous supply of lubricant both through the seal cavity and to the thrust bearing and assures the maintenance of a supply of lubricant 55 in the interior of the seal during the periods when the device is not running, since the only free exit for oil from the interior of the bellows is through the groove 54 which is located near the top thereof as previously noted.

As previously stated, the mean diameter of the portion of the shoe 47 in contact with the collar 42 is the same as the mean diameter of the bellows 43. This provides a substantially balanced seal structure which prevents a tendency for the 65 bellows to be expanded or contracted by changes in internal pressure during the operation of the device. The strength of the spring 48 is sufficient to exert a pressure slightly greater than the product of the unit atmospheric pressure 70 multiplied by the circular area inside the contact face of the shoe 47 on the collar 42.

By the provision of the strength of spring, it is assured that the thrust of the shaft is maintained toward the left, preventing the develop-

ment of end play and keeping the crank member uniformly in contact at all times with its thrust bearing provided by the end of bushing 38. Due to the use of the balanced seal arrangement 5 previously described, it is possible to make the spring 48 of much lighter compressive strength than would be necessary if the latter had to overcome the tendency of the bellows to collapse in case the machine were to operate under partial 10 vacuum. It is obvious that the use of this comparatively light spring keeps wear on the seal and thrust bearing to a minimum, resulting in long life of the parts and effective sealing.

The guiding of the ring 46 by the cylindrical 15 extension 49 of the nut 45 keeps the shoe 47 accurately in alignment with the collar 42 and prevents uneven wearing of the shoe face and subsequent leakage such as occurs due to wobbling of the seal shoe in devices wherein no such guiding 20 means is provided.

The use of the journal sleeve 36 around the shaft extension 31 allows the entire rotative seal and journal assembly to be clamped tightly on the shaft by the crank member 40, the direction 25 of rotation of the shaft being such as to tend to maintain the crank member tightly screwed on its threads. The rotative parts of the motor and compressor thus form a rigid unitary assembly supported in accurately aligned bearings, 30 while the parts are obviously cheap and easy to manufacture and assemble.

The resilient rings 88 and 90 supporting the outside ends of the motor compressor assembly 35 provide cushioning means between the operating parts and the base 20, and due to the fact that this cushion mounting is concentric with the shaft its action in eliminating vibration is distributed throughout the complete 360 degrees of resilient rings. This arrangement is effective 40 in preventing the transmission of motor and torque reaction vibrations to the base and eliminates any loss of the effectiveness of the cushioning such as occurs in structures employing cushion mountings wherein the load is unevenly 45 concentrated on the comparatively small areas of other types of resilient supports.

The above cushion mounting, together with the additional provision of the springs 21 supporting the entire unit, thoroughly precludes the 50 possibility of vibration being transmitted to any cabinet or other structure on which the condenser unit may be mounted in installation.

In the alternative shaft structure shown in Figure 13, the sleeve 36 shown in Figures 1 and 3 55 is omitted, the shaft 139 having an enlarged portion 140 forming the journal which operates in the bushing 38 in the manner previously set forth. The shaft 139 is hardened and has a shoulder 141 against which the sealing shoe 47 60 presses directly, eliminating the collar 42 and washer 42a shown in Figure 1. The shoulder 141 is grooved or undercut at 142 to allow the flat face thereof to be accurately ground. The crank

member 40 is screwed on the threaded end 143 of the shaft 139 so as to tightly engage a second shoulder 144 which is undercut at 145 to ensure flat finishing in manufacture. The operation of the device with the alternative shaft structure 5 shown in Figure 13 is the same as that already described, the alternative structure however allowing the omission of the sleeve 36, collar 42 and gasket 42a from the assembly as noted above.

In the arrangement of the device shown in 10 Figure 11, the unitary condenser block 31 is attached to the motor shell 24 with the cylinder 35 inclined to provide a unit of minimum height, the use of the concentric cushioning ring 88 allowing this arrangement to be made without alteration 15 in the supporting bracket structure.

In this structure the base 133 is shaped as an upwardly facing channel to the sides of which are attached brackets 134 for the springs 21, thus lowering the entire compressor mounting and 20 further minimizing the height of the unit, the condenser 135 being made lower for the same purpose.

To facilitate attachment of the suction line from the cooling unit, the suction shut-off valve 25 127 may advantageously be attached at the right side of the crank-case 34 instead of to the left side as shown in Figure 2.

It will be evident from the foregoing description 30 that the high side or condensing unit structure forms a compact and simple combination, having few and simple working parts assembled with a minimum of bolts and other attaching means, and adapted to quiet operation in conjunction with any suitable type of cooling unit. 35

While the invention has been described in preferred form, it is not limited to the precise structures illustrated, as various modifications may be made without departing from the scope of the appended claims.

What I claim is:

1. In a refrigerating device including a compressor having a discharge opening for compressed fluid and a condenser, silencing means comprising, in combination, an outer shell enclosing a chamber, a perforated tubular member extending into said chamber, means establishing a passage for said fluid from said discharge opening into the interior of said tubular member, and means connecting said chamber to 45 said condenser.

2. In a mechanical refrigerating system, a high side and a low side forming a closed circuit, said high side including a compressor having a rotary shaft adapted to circulate a fluid through said circuit, means to actuate said compressor, annular resilient means disposed concentrically with said shaft and adapted to torsionally absorb vibrations of said compressor and actuating means, and a muffler in said circuit adapted to silence the circulation of said fluid.

LINDSAY H. BROWNE.
